TABLECLOTH

John Graham, Folcroft, Pa., assignor to Quaker
Lace Company, Philadelphia, Pa.

Application January 8, 1954, Serial No. 28,427

Term of patent 7 years

(Cl. D92—26)

To all whom it may concern:

Be it known that I, John Graham, a citizen of the United States of America, residing at Folcroft, in the county of Delaware and State of Pennsylvania, have invented a new, original, and ornamental Design for a Table Cloth, of which the following is a specification, reference being had to the accompanying drawing forming a part thereof, in which the figure is a plan view of a slightly more than quarter section of the table cloth showing my new design, the other three sections being identical with the section here disclosed, arranged in proper relation to complete

the table cloth. The section disclosed is shown over a dark background to bring out the details of the design.

I claim:

The ornamental design for a table cloth, substantially as shown and described.
